UNITED STATES PATENT OFFICE.

GEORGES ROESCH, OF LONDON, ENGLAND, ASSIGNOR OF ONE-HALF TO CLEMENT TALBOT,
LIMITED, OF LONDON, ENGLAND.

RETAINING AND LOCKING DEVICE FOR REMOVABLE BOX ENDS.

1,324,981.

Specification of Letters Patent. Patented Dec. 16, 1919.

Application filed May 7, 1918. Serial No. 233,118.

To all whom it may concern:

Be it known that I, GEORGES ROESCH, a citizen of the Swiss Confederation, residing in London, England, have invented a certain 5 new and Improved Retaining and Locking Device for Removable Box Ends, of which the following is a specification.

This invention relates to an improved retaining and locking device for removable 10 box-ends.

It has been proposed that a large flat tube of wide shallow cross-section should be used crosswise on an automobile under the two chassis longitudinals and should serve not 15 only as a box but also as a cross-stay to bind the two longitudinals together. Such a box could be used to serve as a tire receptacle and as a receptacle for the tool-drawer.

It is to a combined retaining and locking 20 device for the removable door of a box, of which the tube above referred to is a convenient example, that the present invention relates.

Such an open-ended receptacle, *e. g.*, the 25 tube aforesaid, would present a thin margin toward the closing device which would be a door or plate, preferably grooved on its face, to receive or bear upon this marginal portion of the end of the box. Preferably 30 the groove or the face of the door should have a suitable rubber or other soft packing in or upon it for the end of the box to bed upon.

According to the present invention the removable door has on its exterior a rotatable handle permanently secured to the door and from the handle extends through the door into the box interior a screw-threaded extension on which a cross-bar is threaded. 40 The cross-bar engages with lugs fixed inside the box and the manner of its operation and engagement and the method of locking the handle will be hereinafter explained with reference to the accompanying drawings, 45 wherein—

Figure 1 is a vertical cross section of a box-end B and of a door D in it, the construction being provided with a combined engaging and locking device according to 50 this invention;

Fig. 2 is a section, on the line 2—2 Fig. 1, looking from the interior of the box;

Fig. 2^a is a perspective view of the lower part of Fig. 2; and

55 Fig. 3 is an elevation, partly in section of

the middle portion of the outside of the door.

Like letters indicate like parts throughout the drawings.

From these drawings it will be seen that 60 the removable door D has a circular recess r therein, and in the recess is a disk q which is rotatable in the recess but is so held therein by a flange f permanently secured to the door as not to be removable therefrom. The 65 said disk is provided with bolt sockets s spaced apart around its cylindric circumference; these sockets may be conveniently provided by milling with a circular milling tool, the curved recesses s shown in the cylindric circumference of the disk. The disk is formed as or provided with a handle H accessible at the outside of the door, and on the other side of the door it is provided with a screw-threaded extension X which 70 projects from the inner face of the door, through a hole therein. On this extension a cross-bar C is threaded like a nut. A lock 75 K of any suitable type secured permanently in the body of the door is provided with a small key and with a bolt b controllable by said key and adapted to be protruded by the key into or withdrawn from any of the aforesaid bolt-sockets s in the disk q which may come into or may be in register with it. 80

Two lugs L which may be L-shaped are fixed or formed on the inside of the box at opposite sides to engage the opposite ends of the cross-bar C when the door is in place. Each lug has two faces marked respectively 90 1 and 2 in the drawings; one face 1 is positioned to intercept the corresponding arm of the aforesaid cross-bar C when it is being rotated in company with and about the axis of the extension X hereinbefore described, 95 and the other face 2 of the lug is positioned to intercept the arm and prevent it from being moved out of the box by a movement at right angles to the plane of its rotation.

Assuming that the door D is off and that 100 it is desired to close the box-end B, the door is placed against the end of the box and the handle H is rotated. The first effect of this rotation of the handle H will be to rotate the cross-bar C in company with the extension X and bring the ends of the cross-bar into bearing with the faces 1 of the two lugs L; upon this the cross-bar can rotate no farther and continuation of the rotation of the handle will screw the exten- 105 110

sion into the cross-bar and draw the latter home against the second face 2 of each of the two lugs and by the reaction of this operation draw the door D hard up against the end B of the box. One or other of the sockets *s* in the disk *c* will then be found or can be brought opposite the bolt *b* of the lock *K* which can be moved into engagement with it by the small key of the lock, which key can then be removed leaving the disk *q* and handle *H* locked and bolted and the door correspondingly secure.

By unlocking the small lock *K*, the bolt *b* can be withdrawn from the socket in the disk *q* with which it is engaged, and the disk *q* can then be rotated in the reverse direction to that in which it was turned to hold the door on. The first effect of this reverse rotation will be to turn the screwed extension *X* above referred to in the cross-bar *C* and ease its engagement with the lugs *L* which prevent the cross-bar from being withdrawn, and a continuation of this reverse rotation of the extension *X* will cause the cross-bar *C* to rotate with it, and swing clear of both the lugs whereupon cross-bar, extension and door can be moved away in company.

The ends of the cross-bar can have their faces 2° slightly beveled as shown in Fig. 2^a in full line, and the faces of the lugs can be correspondingly beveled; or the ends of the cross-bar can be square and can go into a squared recess in the lugs, shown by chain lines 1, 2, 3 in Fig. 2^a. But whether the lugs be beveled or recessed there is a "return" or rabbet in the depth of the recess

or of the bevel to insure that the bar before it can be disengaged must move backwardly for a short distance (d Fig. 2^a) into the box.

An important advantage of this construction is that when the cross-bar has been tightened by the screw it cannot disengage itself by vibration owing to its engagement in the recess or notch in the stops.

What I claim as my invention and desire to secure by Letters Patent is:—

The combination of a box, a removable door, a rotatable handle mounted on the outer face of the door and provided with a notch in its periphery, a key-operated locking device secured on the door, a bolt in said locking device movable to engage said notch to lock said handle against rotation, a screw-threaded extension of said handle extending through the door and from the inner face thereof, a cross-bar threaded on said extension and frictionally engaging it to be rotatable therewith, an enlarged portion at the end of said screw-threaded portion, lugs on the interior of the box so positioned as to engage said cross-bar when rotated and to prevent further rotation with said handle whereby the cross-bar is traversed along said screw-threaded portion by continued rotation of the handle and stops on the interior of the box notched to receive the ends of the cross-bar and oppose said traversing movement whereby the door is pressed against and closes the box, substantially as described.

In testimony whereof I affix my signature.

GEORGES ROESCH.
